UNITED STATES PATENT OFFICE.

WILLIAM H. HUDSON, OF WYOMISSING HILLS, PENNSYLVANIA, ASSIGNOR TO
ABRAHAM LINCOLN FRAME, TRADING AS GRAY IRON FOUNDRY COMPANY,
OF READING, PENNSYLVANIA.

CONCRETE-MIXER.

1,355,478.

Specification of Letters Patent. Patented Oct. 12, 1920.

Application filed February 12, 1920. Serial No. 358,203.

To all whom it may concern:

Be it known that I, WILLIAM H. HUDSON, a citizen of the United States, residing at Wyomissing Hills, in the county of Berks 5 and State of Pennsylvania, have invented certain new and useful Improvements in Concrete-Mixers, of which the following is a specification.

This invention relates to concrete mixers, 10 the object thereof being to provide a sturdy, simple, compact concrete mixer of small dimensions but having a large mixing capacity and which is speedy in its operation and which also is substantially fool-proof in its 15 mechanism.

A further object of the invention is the provision of an improved concrete mixer in which the mixing blades are so constructed that the aggregates are rapidly carried from 20 the charging end of the drum to a point where the materials are thoroughly and quickly mixed by the blades with a rolling grinding motion as the drum revolves, and in which the blades are so formed that the 25 concrete is lifted or carried after mixing to a point above and directly over the center of the discharge chute and deposited therein.

A further object of the invention is the provision of a concrete mixer so constructed 30 that the blade and the head form a steep sloping deep pocket effective to materially hasten the discharge of the material.

A further object of the invention is the provision of a concrete mixer having improved 35 mixing blades so constructed and located that a perfect mixture of the material is obtained in the shortest possible time.

In the drawings accompanying and forming 40 a part of this specification, Figure 1 is a perspective view of this improved concrete mixer with a part of the drum broken away to show the interior thereof; Fig. 2 is also a perspective view of the mixer from 45 a different point; Fig. 3 is a longitudinal sectional view of the rotary drum with one of the mixing blades in position and a portion of the discharge chute illustrated in dotted lines; Fig. 4 is a cross sectional view 50 taken on line 4—4 of Fig. 3 but illustrating the four blades in position; and Fig. 5 is a detail perspective view of a portion of the inner side of the drum with one of the mixing blades in position.

55 Similar characters of reference indicate

corresponding parts in the several figures of the drawings.

This improved mixer comprises a suitable supporting medium such, for instance, as a carriage comprising a skeleton platform 2, 60 a rear axle and a pair of rear wheels 3, and a swiveled front axle and pair of wheels 4 provided with suitable means as 5 for drawing the mixer to the place where it is to be used. Mounted on this platform is a suitable 65 motor as, for instance, a gas engine 6 for driving the drum. A rotary drum 7 is suitably supported on the platform by flanged rollers 8 having long bearings which permit rotation of the drum and also prevent endwise movement thereof since the flanges of the rolls 8' overlap the projecting flanges or rings 8" of the conical heads hereinafter described.

The drum body is preferably made of 75 sheet steel and secured to the pair of cast iron conical heads by suitable bolts 28. This drum is provided with an exteriorly located sprocket ring 9 which may be made in sections so that it may be readily replaced 80 for the reception of a sprocket chain 10, which also passes around a sprocket wheel on a transversely extending shaft 11. Upon this shaft 11 is fixed a pulley wheel 12 carrying a bolt 13 running to a small pulley wheel 85 14 secured to the fly wheel of the motor, as for instance, a gasolene engine. Pivottally secured to an upright 15 on the carriage is a lever 16 carrying an idler pulley or belt 90 tightener 17, and when this idler is shifted into position near the engine pulley, the belt has more contact with the engine pulley and consequently the drum will be rotated. When this idler is raised the belt will of course slip over the pulley so that the drum 95 is not then rotated. The rotary drum, while small in size, is provided with a pair of conical ends or heads 18, each provided with a centrally located opening, one of which as 19, forms the inlet to the drum and the 100 other, as 20, forms the outlet. By providing these conical heads, the capacity of the drum, although small in size, is materially enlarged.

These conical heads are identical and are 105 provided on the interior of the drum around the openings forming the inlet and discharge with integral deflecting rings 19' and 20' respectively projecting toward the axial center of the drum which prevent 110

the spilling of the aggregates and keep all of the drip inside of the drum and are also formed at the exterior of the inlet and outlet with outside integral drip rings 19" and 20" respectively which project away from the axial center of the drum. The inlet end of the drum is provided with a steep sloping feed chute 22 while the discharge end of the drum is provided with a 10 discharge chute 23 adapted to project into the drum and this chute is swung from a shaft 24 mounted on the discharge end of the drum, and is link connected as at 25 with a hand wheel 26 by means of which the 15 chute may be manipulated. Located within the drum are four mixing blades 27, these blades being so constructed and located that the aggregates are rapidly carried from the inlet end of the drum to the point A (see 20 Fig. 3) of the blades, where the materials are thoroughly and quickly mixed with a rolling and grinding motion as the drum revolves. Each of these blades is troughed as at A, which serves as a pocket to lift or 25 carry the concrete after mixing to a point above and over the discharge chute, at which point a portion of the blade is offset or sloped back as at B so as to have for all practical purposes substantially a beveled 30 position with respect to the rest of the blade, so that the material is carried directly over the center of the discharge chute and deposited in the chute when the latter is inside the drum in its discharge position. In 35 other words, if the mixing blade were so located that it followed a line drawn on the center of the cylinder to the periphery it would mean that when mixing the aggregates the blades would drop the material 40 before they had attained a position over the center of the discharge chute. To prevent this is the reason why the blades are beveled upward from this line, so that they retain the materials for a longer period, 45 thus carrying the materials to the desired point, which is directly centered over the delivering or discharge chute. The mixing blades at the inlet end of the drum run along the cone of the head and together with 50 this cone-shaped head form a steep sloping deep pocket as at C, which materially hastens the carriage of the material to the mixing point and the consequent discharge thereof.

55 The mixing blades run diagonally across the drum and on account of their peculiar design give a perfect mixture in the shortest possible time.

Each mixing blade is bolted to the drum 60 shell or cylindrical face of the drum, that is to say, the wings of each blade are secured to the cylindrical shell of the drum by suitable knees 29, each riveted to the wing or blade and in turn-bolted to the drum shell while the ends of each blade are unat-

tached to the conical heads of the drum. The ends of the four blades adjacent to the inlet end project along the face of the cone head and fit tightly thereto while the discharge ends of the blades terminate in proximity to the outlet end of the drum. 70

It will be observed that each of these blades in a sense has something of the shape of a letter Z, but is so constructed that they are trough-shaped adjacent to the point A, 75 thereby to form a pocket to lift or carry the concrete after it is mixed to a point above and over the discharge chute and that the discharge end of each blade is undercut or beveled back as at B, so that the material will be carried directly over the center of the discharge chute, so that the four blades in operation during the rotation of the drum will not only efficiently and rapidly convey the material from the inlet 80 to the discharge end of the drum, but during the conveyance thereof will efficiently and effectively mix the material in a very rapid manner.

I claim as my invention:

1. A concrete mixer comprising supporting means, a rotary drum supported thereon and comprising a cylindrical shell and a pair of conical ends having centrally located inlet and discharge openings, and a 95 plurality of diagonally located mixing blades positioned within the drum and extending substantially the entire length thereof, each having a trough shaped portion and a portion sloped with respect to the main 100 portion, the sloped portion being adjacent to the discharge end of the drum and unattached thereto.

2. A concrete mixer comprising supporting means, a rotary drum supported thereon, means for rotating it, said drum having a pair of conical ends provided with centrally located inlet and discharge openings, and a plurality of diagonally located mixing blades positioned within the drum, 110 each having a trough-shaped portion and a sloped portion, the latter adjacent to the discharge end of the drum, each of said blades also having a portion projecting along and in juxtaposition to the cone-shaped head at the inlet end of the drum. 115

3. A concrete mixer comprising supporting means, a rotary drum supported thereon, means for rotating it, said drum having a pair of conical ends provided with centrally located inlet and discharge openings, a plurality of diagonally located mixing blades positioned within the drum, each having a trough-shaped portion and a 120 sloped portion, the latter adjacent to the 125 discharge end of the drum, each of said blades also having a portion projecting along and in juxtaposition to the cone-shaped head at the inlet end of the drum, a feed chute secured to the drum at the in- 130

let end, and a shiftable discharge chute secured to the drum at the outlet end and coöperating with the sloped portion of the blades.

5. 4. A rotary drum for a concrete mixer having a cylindrical shell and a pair of conical ends having respectively inlet and discharge openings, and a plurality of mixing blades extending diagonally from one 10 conical end to the other and each having trough-shaped and sloped portions, said trough-shaped portions being attached to said shell and said sloped portions being unattached thereto.
15. 5. A rotary drum for a concrete mixer having a cylindrical shell and a pair of sloping heads provided respectively with a centrally located inlet and discharge opening, and a plurality of diagonally located offset 20 mixing blades secured within said drum and extending substantially the entire length thereof, each of said blades having one end thereof fitting tightly against and conforming to the shape of one of said conical heads, 25 and each thereof having a troughed portion abutting substantially the central portion of said shell.
6. A rotary drum for a concrete mixing machine comprising a cylindrical shell and 30 a pair of conical ends, a plurality of mixing blades extending from one conical end to the other, each blade having a deep trough-shaped pocket abutting the inner surface of said shell and one end located in 35 juxtaposition to one of said conical ends, said blades being attached only to said cylindrical shell, and having substantially the same length as said drum.
7. A rotary drum for a concrete mixing 40 machine comprising a cylindrical body and a pair of conical heads having a centrally located opening, each of said heads having around its opening an inside deflecting ring projecting toward the axial center of the 45 drum, and an outside drip ring projecting away from the axial center of the drum.
8. A rotary drum for a concrete mixing 50 machine comprising a cylindrical body and a pair of conical heads having a centrally located opening, each of said heads having around its opening an inside deflecting ring, an outside drip ring, a feed chute secured to the drum adjacent to the inlet end thereof, a shiftable discharge chute secured to 55 the drum at the outlet end thereof, and a series of mixing blades secured only to the body of the drum and each having a substantially Z-shaped formation.
9. A rotary drum for a concrete mixing 60 machine comprising a cylindrical body and a pair of conical heads having a centrally located opening, a feed chute secured to the drum adjacent to the inlet end thereof, a shiftable discharge chute secured to the 65 drum at the outlet end thereof, and a series of mixing blades secured only to the body of the drum and each having a substantially Z-shaped formation and each provided with a trough-shaped portion terminating in a sloped portion adjacent to the discharge end and in a projecting end conforming to the inlet conical head.
10. A concrete mixer comprising a carriage, a rotary drum comprising a cylindrical body and a pair of conical heads bolted thereto, having centrally located openings, a feed chute secured to one conical head adjacent to the inlet, and a shiftable discharge chute secured to the other conical head adjacent to the outlet, a series of mixing blades secured only to the body of the drum and each having a trough-shaped portion terminating in a sloped portion, the latter located adjacent to the discharge end of the drum and also having an end conforming to the inlet conical head thereby to form a steep sloping deep pocket adjacent to the inlet, a sprocket ring located externally on the drum, a transverse shaft having a sprocket, a sprocket chain coöperating with the shaft and drum sprockets, a pulley wheel on said shaft, a motor on said carriage, and a belt for imparting power from said motor to said pulley wheel thereby to rotate the drum.
11. A concrete mixer comprising a carriage, a rotary drum comprising a cylindrical body having a pair of conical heads bolted thereto, each of said heads having centrally located openings, a feed chute adapted to be connected to one conical head adjacent the inlet, a shiftable discharge chute adapted to be connected to the other conical head adjacent the outlet, a series of mixing blades extending diagonally substantially the entire length of said drum and each having a trough-shaped portion terminating in a portion sloped with respect to the main portion thereof, said sloped portion being located adjacent the discharge end of the drum, and each of said blades having an end projecting along the face of the cone head and fitting tightly thereto adjacent the inlet end of the drum, thereby to form a deep sloping pocket, said blades being attached only to said cylindrical body, means for rotating said drum, and shiftable means for connecting or disconnecting said first mentioned means.
12. A concrete mixer comprising supporting means, a rotary drum supported thereon and comprising a central cylindrical portion and a pair of conical ends provided with centrally located inlet and discharge openings, means for rotating said drum, and a plurality of diagonally located mixing blades positioned within the drum and secured to the central portion thereof with the ends of the blades free of connection with the drum, each of said blades having a

centrally located trough-shaped portion, a delivering portion having a part thereof sloped, and a portion projecting along and in juxtaposition to the cone-shaped head at 5 the inlet end of the drum thereby to form with said head a steep sloping deep pocket.

13. A concrete mixer comprising supporting means, a rotary drum supported thereon; means for rotating it, said drum comprising a central cylindrical portion and a 10 pair of conical ends provided with centrally

located inlet and discharge openings, and a plurality of diagonally located mixing blades positioned within the drum, each having a portion projecting along and in 15 juxtaposition to the cone-shaped head at the inlet head of the drum thereby to form with said head a steep sloping deep pocket.

Signed at Reading, Penna., this ninth day of February, 1920.

WILLIAM H. HUDSON.
